D 14,161

Design No. 14,161, dated August 7, 1883.

UNITED STATES PATENT OFFICE.

HENRY A. WOOD, OF BANGOR, MAINE, ASSIGNOR TO WOOD, BISHOP & CO.,
OF SAME PLACE.

DESIGN FOR A STOVE.

SPECIFICATION forming part of Design No. 14,161, dated August 7, 1883.

Application filed June 26, 1883. Term of patent 7 years.

To all whom it may concern:

Be it known that I, HENRY A. WOOD, of Bangor, in the county of Penobscot and State of Maine, have invented a new and original 5 Design for a Stove; and I do hereby declare that the following is a full, clear, and exact description thereof, that will enable others skilled in the art to which it appertains to make and use the same, reference being had to the accompanying photographic illustration, forming a part of this specification, in which the nature of my invention is clearly shown.

My stove is designed for heating purposes, 15 and is formed on the same general design as that which was secured to me by Letters Patent No. 9,671, dated December 12, 1876, but contains changes and improvements which add much to its beauty. Like that, its general form is rectangular, with molded columns 20 at the corners, a projecting top, and the doors are of a similar pattern; but in my new design

the edges of the projecting top and bottom and around the base *a*, upon which the urn rests, are broad and smooth, without fluting, and the corners *b* of the top are rounded. The urn *c* is also different, being provided with the ornamentation *d* at each side, all these features increasing the attractiveness of the stove. The foot-rail around the hearth also differs, extending around the ends and being supported at the corners by supports *e*. The urn-bottom is also new in pattern, and ornamented as shown.

What I claim as my invention is—

The design for a stove, as herein set forth and as shown in the annexed photographic illustration.

In testimony that I claim the foregoing I have hereunto set my hand this 23d day of June, 1883.

HENRY A. WOOD.
